UNITED STATES PATENT OFFICE.

JOSEPH KOWNACKI, OF SOUTH SAGINAW, MICHIGAN.

VEGETABLE KNIFE.

Application filed August 23, 1928. Serial No. 301,501.

This invention relates to certain new and useful improvements in vegetable knives and particularly to the type having a guard associated with the cutting edge of the blade for varying the thickness of slices, the invention embodying a guard element that is capable of being shifted to a position remote from the cutting edge of the blade when out of use.

10 The primary object of the invention is to provide a vegetable knife of the above type wherein a handle removably receives the shank of a cutting blade while the guard for the cutting blade is carried by a collar 15 rotatably adjustable on the hand with respect to the cutting edge of the blade, the outer end of the blade having a sharpened finger extension for effectively removing eyes and surface pits from different fruits 20 and vegetables.

With the above and other objects in view that will appear as the nature of the invention is better understood, the same consists in the novel form, combination and arrangement of parts hereinafter more fully described, shown in the accompanying drawing and claimed.

In the accompanying drawing wherein like reference characters indicate corresponding parts throughout the several views:

Figure 1 is a side elevational view of a vegetable knife constructed in accordance with the present invention, the guard for the cutting edge of the knife blade being remotely positioned relative to the cutting edge;

Figure 2 is a side elevational view of the knife with the guard in position adjacent the cutting edge of the blade;

Figure 3 is an exploded perspective view showing the several parts of the vegetable knife;

Figure 4 is a cross-sectional view taken on line 4-4 of Figure 1 showing the adjustable collar that carries the knife guard rotatably mounted upon the knife handle; and

Figure 5 is a cross-sectional view taken on line 5-5 of Figure 2.

50 Referring more in detail to the accompanying drawing, there is illustrated a vegetable knife comprising a handle 1 having a reduced annular neck 2 at one end upon which the annular bearing collar 3 is mount-

ed and retained by frictional contact therewith. A rotatably adjustable sleeve 4 is mounted upon the collar 3 with the outer face thereof flush with the handle 1 as shown in Figures 1 and 2. The sleeve 4 is retained in position on the collar 3 and handle 1 by the circular cap plate 5 that is mounted on the outer end of the reduced neck 2 of the handle and there retained by the screw 6 passing through the opening 7 in the cap plate 5 and threaded into the opening 8 in the handle neck 2, the assembly formation being shown in Figures 1 and 2.

The handle 1 and neck 2 are provided with an end opening bore 9 with which the opening 10 in the cap plate 5 registers for the passage of the shank 11 of the blade 10, the blade 12 and cross screw 13 being threaded into the opening 14 in the handle 1 for engaging the shank 11 that is received in the bore 9 to retain the blade in position. The blade 12 is provided at its outer end with a laterally projecting sharpened finger 15 to facilitate the removal of eyes and surface pits from fruit and vegetables.

A longitudinally extending guard rod 16 is carried by the sleeve 4 and has one end rigidly disposed in a tubular bearing 17 projecting laterally from the sleeve. The sleeve 4 in proximity of the tubular bearing 17 is provided with a threaded boss 18 through which a stud screw 19 is threaded for engagement with the collar 3 for holding the sleeve 4 in rotatably adjusted position.

The guard rod 16 may be disposed adjacent the rear edge of the cutting blade 12 when out of use and is capable of being shifted by rotatably adjusting the sleeve 4 to a position adjacent the cutting edge of the blade as shown in Figures 2 and 5 and so retained by the screw 19. The thickness of a cut is regulated by positioning the guard rod 16 at different points in proximity of the cutting edge of the blade 12 and an example of the use on the vegetable is illustrated in Figure 5.

While there is herein shown and described the preferred embodiment of the present invention it is nevertheless to be understood that minor changes may be made therein without departing from the spirit and scope of the invention as claimed.

What I claim as new is:—

In a knife of the character described, a handle having a reduced neck on one end, a collar on the reduced neck, a sleeve rotatable on the collar, a cap plate secured to the outer end of the reduced neck to retain the collar and sleeve in position, a blade detachably connected to the handle, a guard rod

for the cutting edge of the blade carried by the sleeve, and a set screw carried by the sleeve engageable with the collar for retaining the sleeve in rotatably adjusted position.

In testimony whereof I affix my signature.

JOSEPH KOWNACKI.
